UNITED STATES PATENT OFFICE.

JOHN Q. SHERMAN, OF DAYTON, OHIO.

AUTOGRAPHIC REGISTER.

1,268,888.

Specification of Letters Patent. Patented June 11, 1918.

Application filed April 29, 1916. Serial No. 94,300.

To all whom it may concern:

Be it known that I, JOHN Q. SHERMAN, a citizen of the United States, and a resident of the city of Dayton, in the county of 5 Montgomery and State of Ohio, have invented certain new and useful Improvements in Autographic Registers, of which the following is a full, clear, and exact description, reference being had to the accompanying drawing, forming part of this specification.

My invention relates to autographic registers, particularly of the type wherein paper is fed by an operating handle, over a tablet 15 or writing table, and past a tearing blade against which the used strips may be torn off. In registers of this type, it has never been possible in the past so far as applicant has knowledge, to mount the register 20 flush in the top of a desk so that it is out of the way except when it is to be used, and when in use has the same writing surface as has the desk in which it is mounted.

It is accordingly one of the objects of my 25 invention to provide an autographic register which has all of its members accessible from the top of the register, including the operating member for positively feeding the paper and the lid and tablet top, together 30 with the locks therefor, giving access to the inside of the register.

In autographic registers employing the sprocket feed together with perforated paper, to gain perfect alinement, it is necessary to have a form of stripper which lifts 35 the paper strips away from the feeding sprocket and directs them properly beneath the cutting or severing edge against which the used portions are to be torn off of the 40 continuous strip. It is my object to provide a stripper plate which very effectively serves the above function, and also which combines two functions so as to provide a tablet top. It is also my object to so construct the stripper portions of this plate, 45 that they prevent all chances of catching of the paper strips on the edge of the plate and the consequent fouling and crimping of the strips as they are fed from the machine.

50 These objects I accomplish by that certain construction and arrangement of parts to be hereinafter more specifically pointed out and claimed.

In the drawing,

55 Figure 1 is a detail top plan view of the sprocket feed roll operating mechanism.

Fig. 2 is a side elevation of the register in place in a desk or table.

Fig. 3 is a side elevation of the register with the casing broken away to show the 60 internal structure, and the combined stripper and tablet top in section.

Fig. 4 is a top plan view of the register with the lid broken away to show the said stripper and tablet top.

Fig. 5 is a detail plan view of the stripper portion of said tablet top.

The register has sides 1, 1, and a top lid 2 which has a suitable engagement with the lower ends of the register sides. There 70 need be no end walls to the casing as the register is to be sunk so that its top is flush with the surface of a desk or table top 3. The lid of the register is caught at the upper end of the register by means of spring latches 4, 75 which automatically yield to downward pressure of the lid and then spring into engagement with the lugs 5, 5, at the two ends of the tearing blade portion 6 of the said top. In an upstanding housing 7, just behind the 80 tearing blade portion of the top, is suitably mounted a friction roll 8 that serves to hold the paper down against the feed roll, to be hereinafter described, said friction roll being lifted out of frictional engagement during the feeding of the paper, by means not 85 shown and which comprise no part of this invention.

The feed roll 9 has the sprocket teeth 10 which engage in perforations evenly spaced 90 along the edges of the paper strips 11. The roll has a pinion 12 on its shaft, said pinion being located on the left side of the machine outside of the casing. An idler pinion 13 meshes with this pinion 12.

95 Mounted loosely on a stud in the side of the machine is a gear 15 which meshes with the pinion 13 and thereby actuates the feed roll. Integral or connected to the large pinion is a ratchet 16 and mounted outside of 100 the ratchet loosely on the stud is a flat handle 17 which carries a spring pawl 18 for engagement with the ratchet. This handle is thin enough to take up but little room alongside of the machine, and accordingly the machine may be set into the interior of a desk, or below the top of a table, and the handle allowed to extend up along the side of the machine.

105 A stop 19 is mounted on the casing of the machine for the handle, and the handle is provided with a further stop for its operat-

ing movement as follows. On the shaft of the feed roll is mounted a cam disk 20 having a flat edge portion 21. The handle has a cam portion 22, which presents a contact member which will evenly engage the edge 21 of the cam. The ratchet and the pawl on the handle are so positioned that when the handle is against its stop 19 the pawl will be in engagement with one of the ratchet 10 teeth, and the complete swinging forward of the handle will cause the ratchet to move two spaces, that is to say, the distance of two teeth. The cam disk is so positioned that this movement will bring the two contact 15 portions above mentioned into engagement with each other at the end of such motion, and the pinions are so geared that this movement will accomplish one complete rotation of the sprockets so as to feed one 20 designated section of the paper past the tearing point. Thus the handle serves as an overthrow preventer for the feed roll so that it can make but one complete movement at a time, the said handle being a positive 25 stop. The handle will always upon one complete movement from its initial to its final position make one complete feed of a paper section. Some other form of stop and overthrow preventer could be devised which 30 would not depart from the spirit of my invention, and the cam disk is merely the preferred form. The fact that the cam disk is connected direct to the feed roll causes not only the prevention of overthrow of the 35 roll but also causes an adjustment of the paper at the end of the stroke and thus an accurate tearing off.

If desired, some form of spring could be secured to the handle to cause it to move 40 clear back to its initial position when released after its stroke. Such mechanism is not shown as it is not necessary to the operation of the machine.

The tablet top and stripper plate comprises a flat plate 23 of suitable material, 45 which seats on lugs 24 extending inwardly from the side of the casing, and is held in place by bringing the lid down over the top of the machine, so that it bears on said plate. 50 The plate is exposed through the lid in the usual manner in such machines, and at the upper end of the plate it is cut away as follows: The transverse cut 25 is made not quite the length of the feed roll between the 55 toothed members on each end, so as to partially expose the roll. This cut is only wide enough to allow the upper portion of the roll to extend between the two transverse edges 26 of the cut, and these edges are bevelled so that they will allow the roll to move 60 without friction against the plate. Thus the parts may be so positioned that there is a perfectly level space for the paper to pass over, with the roll extending up flush 65 with the surface of the tablet top plate,

for frictional engagement with the paper in connection with the friction roll mounted in the lid. The tearing point is beyond the edge 26 of the cut in the plate that is beyond the feed roll and accordingly the paper lies 70 at all times along the flat surface of the said plate. The feed roll is cut away between the sprockets and the main portion of the roll so that the plate 23 will extend past the inner faces of the two toothed or 75 sprocket members as at 26°. It will be understood that this cut 25 therefore allows the middle part of the roll only to contact with the paper.

Also cut in the plate at each end of the 80 transverse cut, are two independent longitudinal slots or cuts 27, 27, adapted to just clear the sprocket teeth members, and allowing the teeth to extend into contact with the perforations in the paper. The toothed 85 portions are surrounded by the plate at all sides, because of the limited width of the cut 25. If some means interior of the machine is employed to raise the roll 8, a cut or slot would have to be formed outside of the slots 27 to allow this to pass through the plate 23. As this feature of controlling the friction is not part of the invention herein, it is omitted in the plate 23 as well 90 as elsewhere in the drawings. 95

Thus there is provided a simple form of stripper which serves not only as a stripper from the toothed members, but also as a stripper from the feed roll and one which provides practically a complete holding of 100 the paper out of jamming or catching in the feeding devices, while at the same time allowing for the smooth feed of the teeth, as aided by the two opposed rollers on each 105 side of the paper.

A stripper such as the one described could be provided in other types of register, by splitting the portions of the plate beyond the feed roll and teeth away from the tablet 110 top portion, and sliding in this split-off portion from the end of the register. But for a register to be used in a desk, there would be no accessibility for sliding in such a member. Thus in the desk type of register herein developed, the stripper plate has 115 here the additional advantage of being capable of a setting into the register from the top.

I do not wish to be limited in the claims 120 that follow to the exact structure described in the foregoing specification as the description refers but to the preferred form of my invention; on the contrary I wish to be entitled to the full scope of the doctrine 125 of equivalents in the construction of my claims. Also I do not wish to be limited in my claims because of my failure at this time to appreciate the full usefulness of my invention, as I intend it to be used in the future in any manner that may turn out to 130

be economical and convenient, and that mere mechanical changes necessary to adapt it to future uses be fully included in the scope of my invention.

5 Having thus described my invention, what I claim as new and desire to secure by Letters Patent, is:—

10 1. In an autographic register, a casing therefor, a toothed feeding means for paper strips, a roll for carrying said means, and a combined tablet top and stripper plate adapted in one piece to be set into the casing, and cut away around the roll and the toothed feeding means.

15 2. In a autographic register, an operating handle, a toothed feeding means adapted to be rotated by said handle, intermediate gearing between the handle and the said means whereby a partial movement of the handle 20 will cause a complete rotation of said means, and means connected to the said means, and means on the handle to contact with each other at the close of an operation to prevent overthrow.

25 3. In an autographic register, an operating handle, a toothed feeding means adapted to be rotated by said handle, intermediate gearing between the handle and the said means whereby a partial movement of the handle 30 will cause a complete rotation of said means, said means comprising in part a ratchet, and means connected to the said means, and means on the handle to contact with each other at the close of an operation 35 to prevent overthrow, and a stop for the re-

turn movement of the handle as permitted by said ratchet.

4. In an autographic register, an operating handle, a toothed feeding means adapted to be rotated by said handle, intermediate 40 gearing between the handle and the said means whereby a partial movement of the handle will cause a complete rotation of said means, and means connected to the said means, and means on the handle to contact 45 with each other at the close of an operation to prevent overthrow, said means comprising a cam connected to the feeding means, and lying in the path of the handle, and a contact member on the handle for the cam. 50

5. In an autographic register, a casing therefor, a toothed feeding means for paper strips, a roll for carrying said means mounted in the casing, and a stripper plate mountable over the roll, and comprising a cut- 55 away portion for the roll and a cut-away portion for the toothed means.

6. In an autographic register, a casing therefor, a toothed feeding means for paper strips, a roll for carrying said means mounted in the casing, and a stripper plate mountable over the roll, and comprising a cut-away portion for the roll and a cut-away portion for the toothed means, said cut-away portions being separated from each other so 60 as to expose the roll and the toothed means, but to entirely surround the exposed portions of said roll and means. 65

JOHN Q. SHERMAN.
